(57) **CLAIM**

I claim the ornamental design for a golf utility tool, as shown and described.

DESCRIPTION

FIG. 1 is a perspective view of a golf utility tool in accordance with my new design;

FIG. 2 is a front view of the golf utility tool of FIG. 1;

FIG. 3 is a rear view of the golf utility tool of FIG. 1;

FIG. 4 is a right side view of the golf utility tool of FIG. 1, with the left side view of the golf utility tool being a mirror image of that shown in FIG. 4;

FIG. 5 is a top view of the golf utility tool of FIG. 1; and, FIG. 6 is a bottom view of the golf utility tool of FIG. 1.

1 Claim, 1 Drawing Sheet
